(57) **CLAIM**

The ornamental design for a mobile entertainment system, as shown and described.

DESCRIPTION

FIG. 1 is a perspective view of a mobile entertainment system showing my new design.

FIG. 2 is a front plan view of thereof; and,

FIG. 3 is a top plan view of thereof.

The broken lines in the drawings are for the purpose of showing environmental structure and do not form part of the design to be patented.

1 Claim, 3 Drawing Sheets

FIG. 2

FIG. 3
